COMBINATION GARMENT OR THE LIKE

Donna L. Fenlason, Yuma, Ariz.

Application December 15, 1954, Serial No. 33,563

Term of patent 3½ years

(Cl. D3—17)

Fig. 1 is a front elevational view of a combination garment or the like in accordance with the invention; and Fig. 2 is a rear elevational view of the combination garment or the like shown in Fig. 1.

What is claimed is:

The ornamental design for a combination garment or the like, substantially as shown.
